UNITED STATES PATENT OFFICE.

ALBERT L. SESSIONS, OF BRISTOL, CONNECTICUT.

TRUNK STAY.

Application filed February 25, 1922. Serial No. 539,264.

To all whom it may concern:

Be it known that I, ALBERT L. SESSIONS, a citizen of the United States, residing at Bristol, in the county of Hartford and State of Connecticut, have invented certain new and useful Improvements in a Trunk Stay, of which the following is a specification.

This invention relates to a trunk stay for supporting the lid of a trunk in raised position, and has as its object to provide a device of this sort having various features of novelty and advantage, and which is particularly characterized by its simplicity and cheapness in construction and effectiveness in operation.

In the accompanying drawing wherein the preferred embodiment of the invention is illustrated.

Figure 1 is a side elevational view of my improved stay applied to a trunk;

Figure 2 is an edge view of the improved device with the side of the trunk shown in dotted lines; and

Figures 3, 4, and 5, are sectional views taken, respectively, on lines 3—3, 4—4, and 5—5 of Figure 1.

Referring to the drawings in detail, A denotes the body portion of a trunk, B, the lid thereof hinged as at C, and D designates generally the trunk stay for supporting the lid in raised position.

The trunk stay D comprises a pair of pivotally connected links 10 and 11, each preferably formed of a strip of metal, stamped or otherwise cut to shape. The adjacent ends of the links overlap and are hinged together by a pivot in the form of a rivet 13. For the purpose of limiting the pivotal movement of the links, one relative to the other, when the lid is thrown into open position the overlapping end of link 10 has its upper edge turned over as at 14, to provide a lip which rests upon the upper edge of the link 11. The upper edge of the link 10, rearwardly of the lip 14, is cut away as at 15 so that this edge is substantially in line with the upper edge of the link 11 when the parts are in extended position. For the purpose of holding the parts in extended position, as shown in Figure 1, the overlapping ends of the links are provided with an interengaging projection and recess, in the present instance the recess 16^a being provided in the link 11, and the projection 16 which engages in this recess being formed in the overlapping end of the link 10. The

links are made of resilient material so as to permit the projection 16 to ride into and out of the recess 16^a when the trunk lid is brought to, or thrown forwardly out of, 60 raised position.

Adjacent the outer ends of the links 10 and 11 are bosses 17 and 18, respectively, these bosses being apertured as at 19 so as to receive nails or rivets 20 for securing the 65 respective links to the lid and body portion of the trunk. These bosses are substantially partispherical and are adapted to have a bearing at their outer ends against the opposed faces of the trunk parts to which the 70 stay is connected, as clearly shown in Figure 2. The bosses 17 and 18 are formed by pressing the metal of the links out of the plane thereof, and preferably the boss 18 on the inside link 11 is of such size that it 75 extends beyond the plane of the outer face of the link 10, this being of advantage in that the links are held away from the end walls of the trunk and will clear and therefore not interfere therewith when the lid is 80 raised or lowered.

The trunk stay described is of advantage in that the parts may be very cheaply manufactured and installed. The device is relatively strong and will effectively hold the 85 lid in raised position. It also presents a neat and pleasing appearance.

Since the central portion of the stay is spaced from the walls of the trunk by the bosses, the use of burrs or the like between 90 the stay and the trunk lid or body is eliminated and there is no danger of the stay scratching or mutilating the trunk or its lining when the lid is raised or lowered, or of interfering with the lowering of the lid. 95

The recesses in the bosses form countersinks for the heads of the rivets or other fastening means which makes for smoother operation and eliminates the possibility of damage to the lining of the tray from the heads 100 of the rivets.

It is, of course, obvious that my invention is susceptible of many modifications and changes which are within the spirit of the invention without departing from the scope 105 of the following claims, it being understood that the present disclosure of my invention is by way of illustration only and it is not to be taken as restrictive of my conception.

I claim as my invention:—

1. A trunk stay including a pair of pivotally connected links of strip metal and

having adjacent their extreme ends bosses pressed out of the plane of the links and adapted to bear against the trunk parts, said bosses being apertured to receive means 5 for securing the links to the respective trunk parts.

2. A trunk stay comprising a pair of metal strips with overlapping pivotally connected ends, said strips having adjacent their extreme ends centrally apertured bosses formed by bulging the metal out of the plane of the respective strips, both of said bosses extending beyond the plane of the outer strip and adapted to engage the trunk parts, 15 whereby the body portions of said strips are spaced from so as to clear the walls of the trunk to which the stay is secured.

3. A trunk stay comprising a pair of metal strips with overlapping pivotally connected ends, one at least of said strips having adjacent its outer end a parti-spherical boss formed by bulging the metal out of the plane of the strip and beyond the plane of the other one, said boss being centrally aper-

tured to receive means for securing the stay 25 to a trunk.

4. A trunk stay including a pair of metal strips with overlapping ends and adapted to be secured at their extreme ends to the body portion and lid, respectively, of a trunk, a rivet pivotally connecting the overlapping ends of said strips, an interengaging projection and recess on the respective overlapping ends of said strips for holding said stay in extended position when the lid is 35 open, and a lip on the overlapping end of one link adapted to engage the edge of the other link to limit the pivotal movement of the links relative to one another, said lip being formed by turning over the upper edge 40 of the overlapping end of the link, the upper edge of said last mentioned link rearwardly of the lip being inclined so that this edge is substantially in line with the upper edge of the other link when the parts are in 45 extended position.

ALBERT L. SESSIONS.
